REFRIGERATED FOOD DISPLAY CASE

Arthur Perez, James E. Myers, and Faye F. Ibrahim,
Niles, Mich., assignors to Clark Equipment Company

Filed Aug. 21, 1972, Ser. No. 282,540

Term of patent 14 years

Int. Cl. D6—04

U.S. Cl. D6—187

The figure shows a left front quarter perspective view of the refrigerated food display case showing my new design.

The side of the case not shown is a mirror image of the side shown while the back is conventional.

I claim:

The ornamental design for a refrigerated food display case, as shown and described.
